LIQUID COATING APPLICATOR

Filed Jan. 13, 1947

UNITED STATES PATENT OFFICE

2,467,010

LIQUID COATING APPLICATOR

Leonard W. Coley, Beckley, W. Va.

Application January 13, 1947, Serial No. 721,809

3 Claims. (Cl. 91—62.5)

1

This invention relates to applicators for coating compositions, and more particularly to a coating composition-applying apparatus including an applying means, a coating composition-carrying means and a frame rotatably supporting them and swingably supporting one of them. An example of one of the uses of such an apparatus is in applying paint to a surface to be painted.

In the use of many devices of this kind, it is often difficult to dip the coating composition-carrying means deeply into a container, as a can containing the coating composition, and, yet, keep the applying means out of contact with the container and its contents. Moreover, it is fatiguing to then manually retain the coating composition-carrying means in contact with the coating composition-applying means and, at the same time, manipulate the apparatus for carrying out the coating operations.

An important object of the invention is to provide a novel apparatus for applying coating compositions, by which the coating composition-carrying means may be separated from the applying means in such a way as to be readily dipped into a container without causing the first means to contact the container and its contents, since the coating composition-carrying means may be widely spaced from the applying means during the dipping operations.

Another important object is to provide a new apparatus for applying coating compositions, as just described, including means to retain the applying and carrying means in contact without manually holding them in such positions, thus reducing fatigue.

While some liquid coating composition applying apparatus, including composition-applying means and composition-carrying means, may be readily used on vertical surfaces, as walls, or even on horizontal surfaces, as floors, they are not adapted to apply satisfactory coatings to ceilings, due to the effects of gravity upon various parts of the apparatus.

A further object of this invention is to provide a liquid coating composition-applying apparatus which is so constructed that the coating-carrying means will not tend to separate from the coating-applying means while the apparatus is being employed in coating a ceiling.

Still another object is to provide a novel apparatus as described, which is free of coil springs, gears, complicated parts and the like, apt to become broken or get out of order or become gummed together by drying paint.

It is also an object to provide a liquid coat-

2

ing composition applicator which may be manufactured at low cost, and which employs interchangeable applying means as well as composition-carrying means.

5 A further object is to provide an apparatus as desired, which may be arranged to take up but limited space, particularly when arranged with the various parts disposed as in Figures 1 or 5, whereby a relatively flat package will be provided.

Other objects and advantages of the invention will be apparent during the course of the following detailed description of the invention, taken in connection with the accompanying drawing, 15 forming a part of this specification and in which drawing:

Figure 1 is a plan view of the novel coating-composition applying apparatus disposed with the applying means and the carrying means in contact and mounted upon a support.

Figure 2 is a vertical longitudinal section thereof with the means mentioned separated and the carrying means dipped into a container.

Figure 3 is a fragmentary plan view of the 25 support for the means of Figures 1 and 2.

Figure 4 is a longitudinal section through a modification of one of the means of Figures 1 and 2.

Figure 5 is a view, somewhat like Figure 1 but 30 with another modification of the means of Figure 4 mounted upon the support of Figure 3.

In the drawing, wherein for purpose of illustration are shown preferred and modified forms of the invention and wherein similar reference characters designate corresponding parts throughout the several views, the novel applying apparatus is shown to include a handle and support A, upon which are mounted the coating composition-carrying means B, D or F and the 40 composition applying means C or E. A container G is shown, containing a coating composition H.

The handle and support A comprises a portion 10, providing handle and composition-applying means support, a portion 11 providing a composition support, a portion 12 providing a composition-carrying means support, means 13 pivotally connecting the portions 10 and 11, and means 14 to removably retain the portions 10 and 11 (and, consequently, the composition-carrying and composition-applying means) in working positions.

Referring mainly to Figures 1 and 3, it will be seen that the portion 10, which may be a single length of suitable heavy, but somewhat springy wire, is shaped to provide a bight section 15 from 55 which extend spaced apart arms 16, the substan-

tially paralleling sections of which provide a hand hold, and which arms 16 then spread apart as at 17 and which spread apart sections 17 carry the means 13, whereupon the arms preferably again parallel each other, providing the sections 18 which carry portions of the means 12, and finally terminate in inturned sections, providing pivots 19 for the means C or E.

Still referring mainly to Figures 1 and 3, it will be seen that the portion 11, which may also be a single length of suitable heavy, but somewhat springy wire, is formed to provide a bight section 20, arms 21 which first diverge therefrom providing the sections 22 and receive portions of the means 13, then substantially parallel each other, providing the sections 23, which carry portions of the means 12 and finally terminate in inturned sections, providing pivots 24 for the means B or D.

As may be seen in Figures 1 and 3, the portion 11 is inwardly of the portion 10 but, as shown in Figure 2, it may be swung to extend with parts of the sections 23 below and above the horizontal plane of the portion 10.

Two means 12 are provided to pivotally connect the portions 10 and 11 and each may comprise a conventional bolt 30 and nut 31 with both of the former extending through suitable perforations in the sections 18 and 23 of the arms 16 and 21 and suitable spacers 32 may be employed as in Figure 3 to space the sections 10 and 11, so that there will not be any interference of the arms 16 and 22 with each other. It will be noted that the two means 12 are spaced along the sections 18 and 23 so that the sweep or swinging movement of the portion 11 with respect to the portion 10 will permit the means B or D to be separated from the means C or E (as the case may be) a considerable distance (for example, with the axes of the means B and C or D and E about 1½ inches apart).

The means 13 to removably retain the portions 10 and 11 in working positions may be two pairs of spring clips 35. One member of each pair may be secured (as by welding or soldering) to one side of each arm section 17 and the other member of each pair secured to the other side of each arm section 17 so that they are interposed in the path of travel of the arm sections 22, whereby the clips will spring into or out of engagement with the arm sections 22 when the travel of the latter carries them into contact with one or the other of each pair of clips, as is now obvious.

The means B is shown as including an integral cylinder or roller body portion 40 which is preferably of spongy, or coating composition-absorbing material. In fact, it is preferred that it be of sponge and have a longitudinal bore containing a cylindrical insert 41, which is preferably of harder material, such as hard rubber, and suitably secured to the body portion 40, as by an adhesive. As may be seen in Figure 4, there may be provided metallic bushings 42 at the outer ends of the insert to receive the pivots 24, which may be sprung into them.

Referring now to Figures 1 and 2, it will be seen that the means C is shown as a solid cylinder or roller body portion 45, which may be of hard rubber and contain upon its periphery 46, in relief, suitable designs. In the example shown in Figure 1 this design comprises a plurality of spaced-apart, star-shaped figures each comprising a central round section 48 and a plurality of radiating point sections 49. Obviously the same kind of bushings as the bushings 42 may be em-

ployed with the hard rubber cylinder 45, and the pivots 19 sprung into these bushings.

If desired, the means B may be replaced by the means D of Figure 4, a plurality of spaced-apart roller or cylindrical body sections 50, shown in Figure 4 each having a central bore through all of which bores extend a cylinder or insert 51 which is preferably of hard rubber and to which the sections 50 may be secured, in spaced-apart relation, so that a narrow space is between each adjoining section 50. This insert 51 may be equipped with the bushings 42 mentioned. If desired, the means F of Figure 5 may be substituted for the means B or D. The means F is made up of two spaced-apart cylindrical or roller body sections 52 provided with central bores through which extends an insert 53 which may be of hard rubber, secured to the sections 52 as by adhesive, while the body sections 50 and 52 are of coating composition-absorbing material, as sponge.

The means E may be made up of a pair of roller or cylindrical body sections 55, as of hard rubber and provided with a smooth periphery 56, adapted to receive a plurality of spaced-apart coatings of material from the body sections 52.

In using the novel coating composition applying apparatus, when a suitable means, such as the means C, which contains a design or the means E which is plain-surfaced, is selected and mounted upon the pivots 19 and there is also a suitable means B, D or F mounted upon the pivots 24, the portion 11 may be swung to the position shown in Figure 2 and the means B, D or F (as the case may be) dipped into a container of a suitable coating composition, the latter will be soaked up by the means B, D or F. While there is shown, by way of example, a shallow container G for a shallow pool of liquid coating composition H, the container may take any suitable shape, and the pool deep or shallow. In the case of the container G, the means B may be rolled through the pool H. When the sponge portion of the means B, D or F is saturated, the hand of the operator may push down on the bight section 20 while holding the portion 10 steady, and the portion 11 will pivot so that the arm sections 22 will be engaged by the means 13 and this will cause the periphery of the roller body portion 40 to contact the various sections 48 and 49 of the relief design on the roller body portion 45. Now, when the latter is placed in contact with a surface to be painted, and rolled thereover, the coating composition impregnating the roller body portion 40 will be gradually transferred to sections 48 and 49, and, from these, it will be transferred to the surface, as the means B and C rotate.

A combination of the means B with the means E will provide a painted surface without design, but with a narrow unpainted stripe while a combination of means D and E will provide a surface having a plurality of stripes. Obviously, with care, if the means D were dipped into suitable containers each of a different colored coating composition, or a partitioned container, each compartment adapted to contain a different colored coating composition, so that each roller body section 50 soaked up a different colored coating composition, a plurality of different colored stripes would result, all with one sweep of the apparatus. In the event the means D were so treated and the means C associated therewith, the design would be transferred to the surface to be painted, in various colors.

It will be noted that after the operator has

clipped the portions 10 and 11 together by the means 13, he need not strain his hand muscles to retain the two associated composition-carrying and composition-applying means in contact.

As may be appreciated from Figure 2, the portion 11 may be swung to a vertical position, so that the body portion 40 is considerably removed from the body portion 45, for instance, and the former dipped into a container, as a paint can. In any event, the coating composition will not be apt to splash from the container onto the peripheral surface of the body portion 45 (where it might be carried to the surface upon which the design only is intended to be transferred).

Since the portion 11 tends to take a vertical position (due to the weight of the body portion 40) when released by the means 13, the transfer surfaces of the two body portions do not remain in contact. This differs from assemblies where a spring or other means normally urges the composition-carrying means and composition-applying means into contact.

Because the portions 10 and 11 are of wire and one is disposed inwardly of the other so that they may be positioned at the same level when retained by the means 13, at which time the pivotal axes of the two rollers are closest together, the novel apparatus may be rendered particularly compact for packing and storage as well as when in use.

Various changes may be made in the form of the invention herein shown and described without departing from the spirit of the invention or scope of the claims.

What I claim is:

1. In a coating composition applicator, a coating composition-carrying roller; a coating composition-applying roller; means pivotally supporting said rollers for rotation on their longitudinal axes in substantial parallelism, and swingably supporting one of said rollers for moving it into and out of peripheral contact with the other roller, comprising a length of wire providing a handle section, and spaced-apart arm sections extending therefrom and terminating in pivots for one of said rollers, a second length of wire providing a bight section, and spaced-apart arm sections extending therefrom and terminating in pivots for the other of said rollers, and a pair of pivot members pivotally connecting the arm section formed from one length of wire to the arm sections formed from the other length of wire; and a spring-clip means carried by the arm sections formed from one length of wire for engaging the arm sections formed from the other length of wire, to releasably retain both of said lengths of wire in substantially the same longitudinal and transverse planes and, at the same time, retain the pivotal axes of said rollers in positions wherein they are closest together.

2. In a liquid coating composition applicator, a liquid coating composition-absorbing roller having a spongy peripheral portion; a liquid coating composition-applying roller having a hard rubber

peripheral portion; means pivotally supporting said rollers for rotation on their longitudinal axes in substantial parallelism, and swingably supporting one of said rollers for moving it into and out

- 5 of peripheral contact with the other roller in an arc of at least 90°, including a first portion, having a handle section and spaced-apart arm sections extending therefrom provided with inturned pivots at their free ends and extending into one
10 of said rollers, a second portion having spaced-apart arm sections provided with inturned pivots at their free ends and extending into the other of said rollers, and a pivot member for said arm portions disposed intermediate the ends of said
15 arm portions, and means carried by the arm sections of one of said portions for engaging the arm sections of the other portion, to releasably retain both of said portions in substantially the same longitudinal plane, throughout their lengths, and
20 at the same time, retain the pivotal axes of said rollers in position wherein they are closest together and said spongy peripheral portion in intimate line contact with said hard rubber peripheral portion.
25 3. In a liquid coating composition applicator, a liquid coating composition-absorbing roller having a spongy peripheral portion; a liquid coating composition-applying roller having a hard rubber peripheral portion; means pivotally supporting
30 said rollers for rotation on their longitudinal axes in substantial parallelism, and swingably supporting one of said rollers for moving it into and out of peripheral contact with the other roller in an arc, including a first portion, having a handle
35 section and spaced-apart arm sections of resilient material provided with inturned pivots at their free ends and extending into the other of said rollers, and a pivot member for said arm portion disposed intermediate the ends of said arm portions,
40 and means carried by the arm sections of one of said portions for engaging the arm sections of the other portion, to releasably retain both of said portions in substantially the same longitudinal plane throughout their lengths and,
45 at the same time, retain the pivotal axes of said rollers in positions wherein they are closest together and said spongy peripheral portion in intimate line contact with said hard rubber peripheral portions, comprising spring clips
50 mounted upon one pair of said arm sections and interposed in the path of travel of the other pair of said arm sections.
